DESIGN FOR AN ALPHABET FOR MONOGRAMS

Lawrence Wise, Brooklyn, N. Y.

Application May 18, 1938, Serial No. 77,264

Term of patent 7 years

To all whom it may concern:

Be it known that I, Lawrence Wise, a citizen of the United States and resident of Brooklyn, in the county of Kings and State of New York, have invented a new, original, and ornamental Design for an Alphabet for Monograms, of which the following is a specification, reference being had to the accompanying drawing, forming part thereof.

The drawing is a face view of an alphabet for monograms showing the design.

I claim:

The ornamental design for an alphabet for monograms, as shown.

LAWRENCE WISE.
